CLAIM

The ornamental design for a solar wall light, as shown and described.

DESCRIPTION

FIG. 1 is a bottom perspective view of the solar wall light showing my new design;

FIG. 2 is a top perspective view thereof;

FIG. 3 is a top plan view thereof;

FIG. 4 is a bottom plan view thereof;

FIG. 5 is a left side elevation view thereof;

FIG. 6 is a right side elevation view thereof;

FIG. 7 is a front elevation view thereof; and,

FIG. 8 is a rear elevation view thereof.

The broken lines in the drawings are for the purpose of illustrating portions of the solar wall light that form no part of the claimed design.
